UNITED STATES PATENT OFFICE

HERBERT G. M. FISCHER, OF WESTFIELD, NEW JERSEY, ASSIGNOR TO STANDARD OIL DEVELOPMENT COMPANY, A CORPORATION OF DELAWARE

PROCESS OF CONVERTING RESIDUES OBTAINED ON SWEETENING PETROLEUM DISTILLATES

Application filed August 25, 1927. Serial No. 215,302.

This invention relates to the treatment of certain residues obtained on sweetening petroleum distillates and comprehends a process whereby such residues may be converted 5 into more valuable products.

In accordance with a process which is shown in co-pending application, Serial No. 107,787, filed May 8, 1926, sour petroleum distillates are sweetened by contact with added 10 sulfur and a catalyst, followed by distillation, preferably under reduced or sub-atmospheric pressure. This produces a sweetened distillate of low sulfur content and a residue oil containing the sulfur added and 15 much of that originally present in the sour distillate. The sulfur in the residue oil is present mainly in the form of alkyl polysulfides, such as R_2S_3 , etc.

I have found that this residue oil may be 20 converted by heat to an oil of reduced sulfur content, hydrogen sulfide, and hydrocarbon-sulfur compounds of lower boiling point than those originally present in the residue oil. The heat to be applied for this purpose 25 is in excess of 350° F., higher temperatures producing more rapid conversion. This conversion can be carried out by heating the residue oil in liquid and/or vapor phase and under pressure if desired.

If carried out under conditions such that 30 a substantial part of the residue oil is vaporized, the hydrogen sulfide and hydrocarbon-sulfur compounds formed will be found principally in the vaporized part and can be 35 separated therefrom by fractionation. Alternatively, the heating may be carried out under conditions such that relatively little 40 of the residue oil is vaporized, but above 350° F. The mixture of hydrogen sulfide and hydrocarbon-sulfur compounds separates 45 from the residue oil in vapor phase and are separated from each other by condensing the hydrocarbon-sulfur compounds from the mixture and conducting away the hydrogen sulfide gas.

The drawing is a diagrammatic longitudinal section of apparatus adapted to carrying out the preferred embodiment of my process. In operating the same, the residue oil to be decomposed is supplied through pipe 1 to 50 the heat exchanger 2, in which it flows through the multiplicity of tubes 3 and is then conducted through pipe 4, controlled by valve 5, to the tubular heater 6. This consists of a series of tubes joined end to end to form 55 a continuous circuit and is heated by gas burner 7 controlled by valves 8 and 9, as described below. The residue oil is preferably heated in the tubular heater to a temperature of 500 to 600° F. under a pressure which may 60 range from 5 to 50 lbs. gauge.

The oil flows from the tubular heater through pipe 10 and after passing pressure release valve 11 is discharged at atmospheric pressure into separator 12. A part vaporizes in 12, the vapors consisting principally of hydrogen sulfide and hydrocarbon-sulfur compounds of lower boiling point than those originally present in the residue oil. The 65 vapors pass off through pipe 13 to condensing coil 14 supplied with cooling water from any suitable source. The products issuing from 14 through pipe 15 consist principally of liquid hydrocarbon-sulfur compounds and gaseous hydrogen sulfide, and separate in 70 receptacle 16. The hydrogen sulfide passes off through pipe 17 and valve 9 to be introduced into the gas flowing to burner 7 through valve 8 and is thereby effectually disposed of. The 75 liquid compounds are diverted through pipe 18 to cooler 19 and thereafter to any suitable accumulator.

The liquid separated in 12 flows through pipe 20 to the heat exchanger 2, in which it passes in indirect heat interchanging relationship to the residue oil being fed to the tubular heater, thence through cooler 21, and thereafter to any suitable accumulator.

It will be understood that the apparatus specifically shown is in illustration only and 90

that my process may be carried out in various forms of apparatus. Various alternative procedures may be adopted within the scope of the appended claims, in which it is my intention to claim broadly all novelty inherent in my invention.

The term "converting" in the following claims is intended to mean the chemical transformation of the residue oil into an oil of reduced sulfur content, hydrogen sulfide, and hydrocarbon-sulfur compounds of lower boiling point than those originally present in the residue oil.

I claim:

15. 1. The process of converting residue oil containing alkyl polysulfides and obtained by contacting sour petroleum distillates with sulfur in the presence of a catalyst followed by distillation under sub-atmospheric pressure to produce a sweetened distillate and a residue oil, which comprises heating such residue oil to a temperature in excess of 350° F.
20. 2. The process of converting residue oil containing alkyl polysulfides and obtained by contacting sour petroleum distillates with sulfur in the presence of a catalyst, followed by distillation under sub-atmospheric pressure to produce a sweetened distillate and a residue oil containing hydrocarbon-sulfur compounds, which comprises heating such residue oil to a temperature in excess of 350° F. to form hydrogen sulfide and hydrocarbon-sulfur compounds of lower boiling point than those originally present, thereafter separating the hydrogen sulfide and hydrocarbon-sulfur compounds formed from the residue oil.
25. 3. The process of converting residue oil containing alkyl polysulfides and obtained by contacting sour petroleum distillates with sulfur in the presence of a catalyst, followed by distillation under sub-atmospheric pressure to produce a sweetened distillate and a residue oil containing hydrocarbon-sulfur compounds, which comprises heating such residue oil to a temperature in excess of 350° F., but below the temperature of vaporization of a substantial part of the residue oil,
30. 40. 4. The process of converting residue oil containing alkyl polysulfides and obtained by contacting sour petroleum distillates with sulfur in the presence of a catalyst, followed by distillation under sub-atmospheric pressure to produce a sweetened distillate and a residue oil containing hydrocarbon-sulfur compounds, which comprises flowing said residue oil in a continuous stream through a zone of heat for a period sufficient to heat the
35. 45. 50. 55. 60. 65. 70. 75. 80. 85. 90. 95. 100. 105. 110. 115. 120. 125. 130.

same to a temperature between 500 and 600° F. to form hydrogen sulfide and hydrocarbon-sulfur compounds of lower boiling point than those originally present, separating from said heated oil a mixture comprising hydrogen sulfide gas and vaporized hydrocarbon-sulfur compounds, conducting away the residue of heated oil, separating hydrocarbon-sulfur compounds from said mixture by condensing the same, conducting away the hydrogen sulfide gas.

HERBERT G. M. FISCHER.
